UNITED STATES PATENT OFFICE.

ALBERT PARKER, OF PROVIDENCE, RHODE ISLAND.

AUTOMATIC LIGHTING DEVICE FOR AUTOS.

Application filed April 21, 1928. Serial No. 271,882.

The object of this invention is the provision of an automobile circuit maker for lighting the lamps of an automobile or like vehicle at a set period of time.

- 5 A further object is the provision of a device for this purpose that includes an alarm clock which is removably fixed on the instrument board of an automobile or like machine and wherein the alarm mechanism is 10 utilized for actuating a switch connected to the wires of the lamp circuit of the machine so that the said lamps will be automatically illuminated at the time set on the alarm mechanism for such illumination.
- 15 A still further object is the provision of a circuit maker for this purpose that includes an ordinary alarm clock mechanism, which may be readily and easily fixed on the instrument board of the automobile, wherein the 20 winding and hand setting means for the clock is conveniently arranged upon the outer face of the casing therefor and also wherein the means for setting the time at which the circuit maker is to be actuated is 25 also conveniently arranged upon the outer face of the clock casing.

A still further object is the provision of a circuit maker for this purpose which embodies the desirable features of simplicity in 30 construction, cheapness in manufacture and ease and accuracy in operation, and further wherein such operation is wholly automatic.

To the attainment of the foregoing and other objects which will present themselves 35 as the nature of the invention is better understood, the improvement also resides in certain other novel features of construction, combination and operative association of parts, one satisfactory embodiment of which 40 is disclosed by the accompanying drawings.

In the drawings:

Figure 1 is a face view of an alarm clock embodying my improvement.

Figure 2 is a rear elevation thereof.

45 Figure 3 is a side elevation thereof with parts in section.

Figure 4 is a detail view looking toward the face of the clock with parts broken away and parts in section.

50 Figure 5 is a sectional view on the line 5—5 of Figure 4.

Figure 6 is a sectional view on the line 6—6 of Figure 4.

55 Figure 7 is a detail plan view with parts in section, to illustrate the arrangement of

the finger on the gear influencing spring, and the manner in which the said finger overlies the spring switch for holding the same out of engagement with one of the contacts of the circuit.

Figure 8 is a sectional view approximately on the line 8—8 of Figure 7, the finger having been moved by the spring to release the switch.

In the embodiment of the improvement 65 disclosed by the accompanying drawings the clock casing 1 has fixed on its outer face a plate 2 which is designed to be bolted to the instrument board of an automobile after the casing has been let through an opening 70 in such instrument board. The clock is of the usual construction and embodies an alarm mechanism. In the present instance, however, the alarm is dispensed with, but the gear 3, which is loosely mounted upon 75 the shaft 4 is employed, the said gear being in mesh with the usual pinion 5 and being slideable upon said pinion to permit of the said gear being brought into locking engagement with the shaft 4 for actuating 80 the tappet means of the alarm. This construction is old and well known in the art. The gear has on its outer face the usual hub extension 6 which is notched, as at 7, and the shaft 4 carries a pin 8 to be received in 85 the notch of the hub when the train of gears of the clock have turned the gear 3 to the position indicated by the hand 9 on the outer end of the shaft 4 when the alarm is to be sounded.

90 Fixed on a suitable support in the casing 1, and having an opening therethrough for the free reception of the shaft 4 there is the usual flat or arched spring 10 which influences the gear 3 in its longitudinal movement and to bring the notched portion 7 thereof to engage with the pin 8 on the said shaft 4. This is also of the usual construction.

95 The outer and free end of the spring 10 has secured thereon in any desired or suitable manner an inwardly extending flexible finger 11, the same being preferably in the nature of a spring rod. This rod has its outer end guided through slots 12 that 100 enter from the ends of the bifurcated portion 13 of a block 14 of insulating material. The block is secured to another block 15 which is also of insulating material. This block 15 has arranged thereon a binding 105 110

post 16 for one of the wires of the lamp circuit, the said binding post 16 being disposed to one side of the block 14, while also fixed on the block 15, to the opposite side of the block 14, there is the second contact 17 for the lamp circuit. I have not deemed it necessary to illustrate the lamps nor the circuit therefor as the same are of the ordinary type employed upon automobiles or like vehicles having an electric system.

By reference to Figure 8 it will be seen that the contacts 16 and 17 are arranged below the shoulder provided in the block 14 by the bifurcated portion 13 and also by reference to this figure and likewise to Figure 6 of the drawings it will be seen that there is fixed on the binding post 16 the coiled end of a spring switch member 18 which is guided through the bifurcated portion 13 of the block 14.

In the showing of the drawings, the winding shaft of the clock has fixed on its end which projects through the back of the casing 1 a gear 19 which is in mesh with a similar gear on a shaft 20 which is journaled in suitable spaced bearings 21 in the said back or rear of the casing. On the second end of the shaft 20 there is fixed a second gear which is in mesh with the gear 22 whose shaft 23 is extended through the face 2 of the casing and has fixed thereon an operating handle 24. The shaft 23 is guided through the hollow shaft 25 of the hand set mechanism. This shaft 25 is journaled through a suitable bearing opening in the face plate 2 and through a bearing 26 which is fixed to and depends from the casing 1. The outer end of the shaft 25 has fixed thereon an operating handle 27. The periphery of both the handles 24 and 27 are knurled and the inner end of the hollow shaft has fixed thereon a gear which is in mesh with a similar gear of a shaft 28 that is journaled through suitable bearings 29 in the rear of the casing 1. The second end of the shaft 28 has a gear which is in mesh with a similar gear 29' connected with the shaft of the hand set mechanism.

The shaft 4 has fixed on its rear end a gear 30 which is in mesh with a similar gear on a transversely arranged shaft 31 that is journaled in suitable spaced bearings on the rear face of the clock, the said shaft 31 having fixed on its second or outer end another gear which is in mesh with a similar gear on the end of a shaft 32. This shaft is extended longitudinally through suitable bearings and passes through the face 2 of the clock and has on its outer end a knurled operating handle 33. By this construction it will be seen that the clock may be wound, the hands may be set and the indicator hand for the wheel 3 may be set from the outer face of the clock.

The operation of the improvement may be

briefly described as follows: The hand 9 is set to arrange the lug 8 in contact with the hub 6 of the gear 3, the said hand 9 being disposed opposite one of the fingers on the dial 34 therefor. Thus the train of gears of the clock will turn and slowly revolve the wheel 3 until the notch of the same is brought in a line with the lug 8 on the shaft and thereafter the spring 10 will influence the gear to move the same longitudinally on the shaft 4 and to cause the lug to be received in the notch 7 in the hub of the said gear. Obviously such movement of the spring will impart a longitudinal movement to the finger 11, partly drawing the same through the slot 12 which provides the guide for the said finger. It should have been stated that the spring switch 18 is influenced to bring the same beneath the finger 11 and, therefore, out of engagement with the contact 17. It will be obvious that when the switch is brought against the contact 17 the circuit will be completed and the lamps will be illuminated. It will be likewise apparent that means must be provided for swinging the circuit maker comprising the switch 18 away from the contact 17 when the lamps are to be shut off. To accomplish this I journal in a suitable bearing 35 in the casing 1 the straight portion 36 of a shaft which has its ends bent in opposite directions. One end of this shaft is indicated for distinction by the numeral 37 and passes through an elongated slot 38 in the face plate 2; the second end, indicated for distinction by the numeral 38', being provided with a socket 39 in which there is inserted and secured a rod or finger 40 of insulating material. The finger 40 is disposed directly over the switch or circuit maker 18 as shown by Figs. 4, 6 and 8 of the drawings. Obviously by swinging the handle end 37 of the shaft 36 the finger will be brought against the spring switch or circuit maker 18 to move the same away from the contact 17, causing the said switch to glide over and be arranged beneath the spring finger 11.

The simplicity of my improvement and the advantages thereof will, it is thought, be understood and appreciated by those skilled in the art so that further detailed description will not be required. It should be stated, however, that the lamp circuit may be controlled by the usual switch and likewise that I do not wish to be limited to the precise details of construction as herein set forth as I hold myself entitled to make such changes therefrom as fairly fall within the scope of what I claim.

Having described the invention, I claim:

The combination with a rotary wheel having a hub provided with a cam depression, a train of gears including a pinion in mesh with the wheel, a shaft on which the wheel is freely mounted having a lug in contact

- with the hub thereof, a flat spring for influencing the wheel longitudinally on the shaft to bring the lug on the shaft into the cam depression when the wheel has turned 5 for a predetermined distance, of a lamp circuit maker, comprising a resilient finger carried by the spring, a guide for the finger, a binding post for one of the wires of a lamp circuit, a contact disposed opposite 10 the binding post, a spring switch secured on the binding post and swingable against the contact, a guide for the switch, said switch designed to be normally disposed beneath the finger and held away from the contact when the wheel is in normal position, 15 and to be released from engagement with the finger when the wheel is moved longitudinally and an operating lever to contact with the switch to flex the same beneath the finger when the wheel is returned to its normal position. 20

In testimony whereof I affix my signature.

ALBERT PARKER.
